Primary Examiner — Brett Miller*Assistant Examiner* — Jessica M Gebhart(74) Attorney, Agent, or Firm — Kilpatrick Townsend & Stockton LLP(57) CLAIM

The ornamental design for an infant carrier with ties, substantially as shown and described.

DESCRIPTION

FIG. 1 is a perspective view of an infant carrier with ties showing my new, original, and ornamental design when worn by a user;

FIG. 2 is a front view of the infant carrier with ties, shown when not worn by a user and in an open configuration;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines depict environment and portions of the article that form no part of the claimed design.
